UNITED STATES PATENT OFFICE.

ERNEST L. PATTEN, OF NEW HAVEN, CONNECTICUT, ASSIGNOR TO L. CANDEE & COMPANY, A CORPORATION OF CONNECTICUT.

LAST-HOLDING DEVICE.

Application filed February 9, 1922. Serial No. 535,118.

To all whom it may concern:

Be it known that I, ERNEST L. PATTEN, a citizen of the United States, residing at New Haven, county of New Haven, and 5 State of Connecticut, have invented a certain new and useful Last-Holding Device, of which the following is a full, clear, and exact description.

This invention relates to a last holding 10 device for use in the manufacture of footwear, and more particularly to one for employment in the making of rubber or canvas and rubber footwear.

In the making of rubber footwear, the 15 usual method is to build up the article piece by piece by superposing the pieces on a last and compacting them by means of a hand roller, the operator holding the last in one hand while rolling with the other. This 20 does not allow the operator free use of both hands during the building up operation and necessitates a great deal of handling of the last, which is particularly objectionable in the making of white rubber footwear and 25 white canvas goods, owing to the soiling of the goods by the hands of the operator. In addition, whenever it is desired to exert greater pressure than usual the operator usually steadies the last against the chest 30 with one hand while rolling with the other, which involves considerable effort on the part of the operator, and is wasteful of energy.

An object of my invention is to provide 35 a last support for use in the making of footwear which will reduce the time and labor required in making the same.

Another object is to provide a last support having a maximum number of adjustments and which may be adjusted with a minimum of effort.

Still another object is to provide a last support, which while of particular application in the building up of rubber footwear 45 on a last, is also of general application in the footwear art.

For a detailed disclosure of the invention reference is had to the accompanying specification and drawing, in which latter:

50 Figure 1 is a side elevation, partly broken away; of the device;

Figure 2 is an end elevation;

Figure 3 is a top plan view, partly broken away;

Figure 4 is a side elevation of a slightly 55 modified form of support;

Figure 5 is a plan view of the last supporting bracket shown in Fig. 4;

Figure 6 is an end view thereof; and

Figure 7 is a plan of one form of work- 60 bench for use with the last support.

Referring to the drawing, the numeral 1 designates a table or work bench and below the bench is a stringer 1' to which is secured the bracket 2, the latter having at its 65 outer overhanging end a split collar 3 adjustable by the clamping screw 4. Secured in the split collar is a tubular column 5 from the upper end of which projects a bracket 6 having at its free end a flat circular bearing 7, from the center of which projects upwardly a pivot pin 8. A yoke member 9 is rotatably mounted on the pin 8, and at its lower end is provided with a flat circular bearing 10 coacting with the bearing 7, the yoke member being held in position on the pivot pin 8 by means of the nut 11. To frictionally secure the yoke member 9 in adjusted position a spring pressed 70 detent 12 is provided in the bearing 7, which detent is adapted to coact with any one of the circularly disposed series of recesses 13 in the bearing 10. These recesses may be formed directly in the bearing 10, but preferably, and as shown, they are formed in 75 hardened bearing blocks 14 inserted in the lower face of the bearing 10. Mounted in the upper free ends of the yoke member 9 are pivot screws 15 secured in adjusted position 80 by lock nuts 16. Pivotaly mounted on the screws 15 between the arms of the yoke is a block 17 having at one side a sector plate 18 provided with stops 18'. A spring pressed detent 19 is mounted in one of the 85 arms of the yoke 9 in position to coact with the recesses 20 on the sector 18, which recesses are preferably formed in hardened blocks 21 set into the face of the sector 18. The stops 18' by engaging the casing of 90 detent 19, limit the movement of the sector 18 to 90° each way.

The block 17 is formed with a circular bore 22 in which is rotatably mounted a socket member 23 having on its upper end

a head or flange 24 adapted to frictionally engage the block 17. Loosely mounted on the lower reduced end of the socket member 23 is a sleeve 25 having a flange 26 adapted to frictionally engage the lower end of the block 17 around the edge of bore 22. Relative rotary movement of the sleeve 25 and socket member 23 is prevented by a pin 27 engaging recesses in the socket member 10 and sleeve. A nut 28 is threaded on the lower end of the socket member and interposed between this nut and the flange 26 is a coil spring 29, which by its expansion is adapted to cause the flanges 24 and 26 to frictionally engage the block 17.

The socket member 23 is provided with a tapered socket 30 in which is adapted to be driven the tapered socket pin 31, which latter has secured to its upper end a last supporting bracket or element 32 provided with spaced pins 33 on which the last 34 may be supported in the usual manner.

In the form shown in Figs. 4 to 6 the parts up to and including the block 17 and its adjustments are the same as in the form shown in Figs. 1 to 3. Instead of mounting the socket member 23 in the bore 22 of the block 17, however, a shank or pivot pin 35 is rotatably mounted in the bore, which 25 shank has an enlarged head 36, the lower side 37 of which is adapted to frictionally contact with the block 17 around bore 22 in the same manner as the head of socket member 23. A keyway 38 is cut in the lower 30 end of the shank 35, and a washer 39 is loosely disposed around the lower reduced end of the shank. This washer has a key 40 projecting from its inner periphery and disposed in the keyway 38, thereby preventing 35 relative rotary movement of the shank 35 and washer 39. A knurled thumb nut 41 is threaded on the lower end of shank 35 and a coil compression spring 42 is interposed between the nut and washer 45 39, said spring causing the lower side of the head 36 and the washer 39 to frictionally engage the block 17 in the same manner as the flanges 24 and 26 in the form shown in Fig. 1. A tapered dovetail groove or keyway 43 is formed on the upper side of the head 36, and a last supporting bracket 44 is provided at one end with a tapered dovetail portion 45 adapted to have a wedge fit in the groove 43, the bracket 44 being provided with the usual last supporting pins 46 on which may be mounted the last 47.

In operation of the form shown in Fig. 1 the last supporting element 32 is secured in the socket member 23 by driving its socket pin 31 into the socket 30. The pins 33 are variably spaced for different sizes of lasts, and in practice brackets 32 having variously spaced pins 33 are provided. Whenever it is desired to change one last supporting bracket for another the change may be

readily made by merely tapping the bottom of the tapered socket pin 31 to loosen the same, when the bracket 32 may be removed and another with differently spaced last pins 33 substituted.

The operator then loosens clamping screw 4 on collar 3, allowing the column 5 to be vertically adjusted to any desired height, after which the clamping screw may be again tightened. After placing the last 34 76 on pins 33 the operator proceeds in the operation of building up a shoe. It is convenient, when beginning, to rotate the yoke 9 on its bearings to a position 90° away from that shown in Fig. 1, that is, with the arms 80 of the yoke in a line parallel with the front edge of the table shown in Fig. 7. In this position the block 17 may be turned 45 or 90° toward or away from the operator, thereby correspondingly inclining the last. 85 In any of these positions the last and its supporting bracket may be rotated through any part of 360° on the block 17. It is convenient for some purposes, as when lasting the lining on the insole, to incline the block 90 17 45° toward the operator, and then to rotate the last support 32 in the block to any desired position during the lasting. In applying the toe tip the block 17 may be rotated 90° away from the operator, and the 95 last then rotated to bring the toe upwardly. On the other hand, in applying heel parts it is most convenient to rotate the block 90° toward the operator and rotate the last to bring the heel portion upwardly. In rolling 100 the sides of the shoe it is most convenient to turn the yoke 9 to the position shown in Fig. 1, when the block 17 may be swung 45 or 90° laterally to either side. The above 105 description is merely illustrative of the numerous adjustments which may be obtained with the device, and it is particularly to be noted that in any position of the yoke 9 or block 17 the shoe last may be rotated through 360° on the block 17, thereby allowing 110 the operator to obtain ready access to every part of the shoe. As the rotation of the last and its supporting bracket 32 in the block 17 is the adjustment most frequently used, the spring 29 is so regulated that 115 the last may be frictionally adjusted in this manner without disturbing the adjustment of the yoke 9. It will be seen that by reason of the adjustment of the block 17 on a horizontal axis the last and supported 120 footwear article may be disposed in different positions with respect to the vertical and at either side thereof, the fixed stops 18' limiting this movement to 90° on either side of the vertical. When the device is not in 125 use it may be swung back over the table, if desired, by first loosening the clamping screw 4.

The operation of the form shown in Figs. 4 to 6 is in all respects similar to that of the 130

form shown in Fig. 1, with the exception of the manner of changing the last supporting bracket for different size lasts. This change may be made by merely tapping on the outer 5 end of the tapered dovetail portion 45 of the last supporting bracket, and driving in another bracket having differently spaced last supporting pins 46. In both forms of the invention a quick detachable connection 10 is provided which allows of ready exchange of the last supporting element for different sizes.

It will be seen that by my invention a last support has been provided which is capable 15 of a large number of adjustments in various directions, the adjustments can be made with a minimum expenditure of time and labor, and the support will frictionally retain the position to which it has been adjusted. In 20 the building up of rubber footwear a large number of operations are required, and it is essential to economical manufacture that these operations be performed with the greatest ease and speed. Hence, it is not 25 practicable to use a last support in which the parts after adjustment must be locked in position by set screws or similar devices, as the time occupied in loosening and securing such devices for each change of the 30 last support would lengthen the time required in the making of a shoe to such an extent as to make the cost prohibitive. As previously pointed out it has been common, prior to my invention, for the operator to 35 hold the last in one hand while performing various operations, such as rolling, stitching, etc., with the other. In addition to the excessive manual labor required this manner of holding the last and article causes an 40 objectionable soiling of the article in cases where white rubber or other material is being used. As far as I am aware I am the first to provide a readily adjustable last support suitable for the manufacture of 45 rubber footwear. It will entirely obviate the holding of the last against the body by the operator while hand rolling any of the parts, and it will increase the output of the operator while reducing the physical effort 50 required. While the support has been particularly designed for use in the making of rubber footwear or canvas and rubber footwear, such as tennis shoes, and similar articles, it is obvious that it is of general application in the footwear art.

Having thus described my invention, what I claim and desire to protect by Letters Patent is:

1. A shoe last support comprising a last 60 supporting element, means whereby the same may be adjusted including successive rotary adjustments on vertical, horizontal and vertical axes, variable yielding means for frictionally retaining said first adjustment, a 65 base, and vertically adjustable means for

supporting said previously named parts on the base and in offset relation thereto.

2. A shoe last support comprising a last supporting element, means whereby the same may be adjusted including successive rotary 70 adjustments on vertical, horizontal and vertical axes, yielding and fixed stops for retaining said second adjustment, a base, and vertically and rotatably adjustable means for supporting said previously named 75 parts from the base on a vertical axis in offset relation to the base.

3. A shoe last support comprising a last supporting element, means whereby the same may be adjusted including successive 80 rotary adjustments on vertical, horizontal and vertical axes, yielding means for frictionally retaining each of said adjustments, a base, and means for adjustably supporting said previously named parts on the base and 85 in offset relation thereto.

4. A shoe last support comprising a last supporting element, means whereby the same may be adjusted including successive 90 rotary adjustments on vertical, horizontal and vertical axes, yielding means for frictionally retaining each of said adjustments, a base, rotatably adjustable means for supporting said previously named parts on the 95 base and in offset relation thereto, and means for retaining said last named means in adjusted position.

5. A shoe last support comprising a last supporting element having spaced last receiving pins, a support for the same rotatably adjustable on a vertical axis, a quickly detachable connection between the two, means for rotatably supporting said previously named parts on a horizontal axis, means for supporting the preceding parts on a vertical axis, a base, and means for vertically or rotatably adjusting the entire mechanism on the base.

6. A shoe last support comprising a quickly detachable last supporting element, having spaced last receiving pins, a plurality of means whereby the same may be frictionally adjusted in a plurality of directions, a base, and means whereby said first means may be vertically or rotatably adjusted on the base.

7. A shoe last support comprising a last supporting element having a tapered attaching portion, a member having a tapered recess adapted to receive said portion with a wedge fit, means whereby said member may be rotated, and successive means whereby said member may be rotated in planes at right angles and parallel to the plane of said first rotation.

8. A shoe last support comprising a last supporting element having a tapered attaching pin, a socket having a tapered bore adapted to receive said pin, means for mounting said socket for rotation in a horizontal plane, means for mounting said first 130

means for rotation in a vertical plane, and means for mounting all of said previously named parts for rotation in a horizontal plane.

- 5 9. A shoe last support comprising a base, a rotatably and axially adjustable bracket mounted thereon, means for securing the bracket in adjusted position, a frictionally held yoke member rotatably adjustable on 10 said bracket, a frictionally held block rotatably adjustable in said yoke member in a plane at right angles to the adjustment of the yoke member, and a frictionally held last supporting element adjustable in said 15 block in a plane at right angles to the adjustment of the latter.

10. A shoe last support comprising a base, a bracket rotatably and axially adjustable

thereon, means for securing the bracket in adjusted position, a yoke member rotatable on said bracket, means for yieldingly holding the yoke member in any one of a plurality of adjusted positions, a block rotatably adjustable in said yoke member in a plane at right angles to the adjustment of the latter, means for yieldingly holding the block in any one of a plurality of adjusted positions, a last supporting element rotatably adjustable in said block in a plane at right angles to the adjustment of the latter, so and means for frictionally holding said element in any adjusted position.

Signed at New Haven, in the county of New Haven and State of Connecticut, this 2nd day of February, 1922.

ERNEST L. PATTEN.
